UNITED STATES PATENT OFFICE.

MATHIAS FLAMMANG, OF NEWARK, NEW JERSEY, ASSIGNOR TO THE SCOVILL MANUFACTURING COMPANY, OF NEW YORK, N. Y.

SHUTTER MECHANISM FOR PHOTOGRAPHIC CAMERAS.

SPECIFICATION forming part of Letters Patent No. 377,554, dated February 7, 1888.

Application filed October 17, 1887. Serial No. 252,560. (No model.)

To all whom it may concern:

Be it known that I, MATHIAS FLAMMANG, of Newark, county of Essex, State of New Jersey, have invented a certain new and useful Improvement in Shutter Mechanism for Photographic Cameras, of which the following is a specification.

My improvement relates to shutter mechanism of the kind known as "fly-shutter" mechanism, and which is employed in instantaneous photographs.

The object of the improvement is to provide a simple, cheap, and effective means whereby a spring employed for effecting the fly-shutter may have its force varied to expedite or reduce the rapidity of the fly-shutter.

I will describe an apparatus embodying my improvement, and then point out the novel features in the claims.

20 In the accompanying drawings, Figure 1 is a front view of a board or piece arranged in the front portion of the case of a camera. Fig. 2 is a back view of the same.

Similar letters of reference designate corresponding parts in both figures.

25 A designates a board or piece which is arranged in the front portion of the case of a camera. It is provided with a circular opening which is to be opposite the lens-tube of the camera.

30 B designates a disk, which may be made of thin metal, india-rubber, or like material, and is provided, as here shown, with two circular holes. It is arranged adjacent to the front side of the board or piece A. At the center it is mounted on a shaft, b, which is supported in the board or piece A and in a frame, a', affixed to the latter. A pulley, b', is arranged at the front of the disk, and another pulley, b'', is arranged at the rear of the board or piece A. These pulleys are mounted upon the shaft b and may rotate thereupon. They and the disk are secured together, so as to move in unison. A simple way of securing them together is to 40 extend a hub from one of the pulleys through the disk and into the other pulley. A cord, c', is fastened to the pulley b', passed around the same, and connected to a pull-piece, C. A cord, c'', is connected to the pulley b'', and after 45 being wound around the same is connected to a spring, D.

The spring D consists of a piece of wire wound around a stud, d', and having one end extended to another stud, d'', and the other end extended over beneath the pulley b'', so as to 55 form a long arm. The long arm is connected to the cord c''. By moving the pull-piece C outwardly the cord c' will be unwound from the pulley b', and in being unwound will rotate the pulley b', the disk B, and the pulley b'', and as 60 the cord c'' is wound in the reverse direction from the cord c' the cord c'' will at this time be wound upon the pulley b''. Of course as it is wound upon the pulley b'' it will deflect the long arm of the spring D and put the same under additional tension. When the pull-piece is released, it will move back to its original position and slacken the cord c', so as to permit it to be rewound again upon the pulley b' whenever the pulley b', the disk B, and pulley b'' 65 shall be rotated in the reverse direction.

70 The disk B is shown as provided with a projection, b⁴, which, when the disk is rotated by moving out the pull-piece, will come in contact with a stop, b⁵, affixed to the front of the board or piece A. This projection, when the disk is rotated in the opposite direction, will engage with a spring-detent, b⁶. When the disk shall have been rotated as far as possible by the pull-piece, a spring-actuating detent, E, will engage 75 with a notch in the edge of the disk to retain the disk in position. This detent is provided with a hand-piece, e, which may be pressed upon to disengage the detent and release the disk. Whenever the disk shall be thus released, the spring D will unwind the cord c'', and thereby rotate the pulley b'', the disk B, and the pulley b'. The rotation of the pulley b' causes the cord c' to be wound upon it again.

80 G designates a lever fulcrumed between the ends to the board or piece A, or to an appurtenance thereof. Its lower end is made in the form of a hand-piece, and is intended to protrude through the case of the camera. Its upper end is provided with a screw or other projection, 85 g, which bears upon the long arm of the spring D. By swinging or vibrating this lever G its projection g may be made to act upon the long arm of the spring D at different distances from the fixed end of said arm, and thereby to subject the spring to a greater or less tension. 90 Accordingly as the tension is varied so will be 95 100

the speed of the movement of the disk B forming the fly-shutter.

It will be seen that the mechanism which I have provided for varying the speed of the fly-shutter is simple, cheap, and withal very effective.

What I claim as my invention, and desire to secure by Letters Patent, is—

1. In a fly-shutter mechanism of a photographic camera, the combination of a board or piece provided with an opening, a rotary disk supported upon said board or piece, a pulley secured to said disk, a cord wound upon said pulley, a spring having an integral portion constituting an arm connected to said cord, and a lever having a projection impinging upon the said arm of the spring, substantially as specified.

2. In a fly-shutter mechanism of a photographic camera, the combination of a board or piece provided with an opening, a rotary disk supported upon said board or piece, two pulleys affixed to opposite sides of said disk and rotating with it, a cord wound upon one of the pulleys, a pull-piece connected to this cord, a spring also connected to this cord, a cord reversely wound on the other pulley, a spring having an integral portion constituting an arm connected to the last-named cord, and a lever having a projection impinging upon said arm of the spring, substantially as specified.

M. FLAMMANG.
